Attorney, Agent, or Firm—Moore, Foard & Dias; Richard M. Foard, atty.

[57] CLAIM

The ornamental design for a flagpole, as shown and described.

DESCRIPTION

FIG. 1 is a front elevation view of the flagpole; FIG. 2 is a rear elevation view of the flagpole; FIG. 3 is a right side elevation view of the flagpole; FIG. 4 is a left side elevation view of the flagpole; FIG. 5 is a top view of the flagpole; FIG. 6 is a bottom view of the flagpole; and, FIG. 7 is an in-use perspective view thereof. All broken away portions are to show indeterminate length. The broken line showing of a flag in FIG. 7 is for illustrative purposes only and forms no part of the claimed design.
